United States Patent Office

Des. 193,332
Patented Aug. 7, 1962

193,332

STEP FOR A TRUCK

Lee J. Crain, Bakersfield, Calif., assignor to Superior Industries, Inc., North Hollywood, Calif., a corporation of California

Filed July 10, 1961, Ser. No. 65,870

Term of patent 14 years

(Cl. D14—6)

Fig. 1

Fig. 2

Fig. 3

The bottom, not shown, is substantially plain.

I claim:

The ornamental design for a step for a truck, substantially as shown and described.
